UNITED STATES PATENT OFFICE.

JOHN KORANEK, OF CHICAGO, ILLINOIS, ASSIGNOR TO WHITE BRASS CASTINGS COMPANY, OF CHICAGO, ILLINOIS, A CORPORATION OF ILLINOIS.

CLOSURE FOR COIN-SLOTS.

1,286,653.

Specification of Letters Patent.

Patented Dec. 3, 1918.

Application filed October 18, 1917. Serial No. 197,221.

To all whom it may concern:

Be it known that I, JOHN KORANEK, a citizen of the United States, and a resident of the city of Chicago, county of Cook, and 5 State of Illinois, have invented certain new and useful Improvements in Closures for Coin-Slots, of which the following is a specification.

My present invention has relation to the 10 provision of an improved closure for slots in banks, and has special reference to the provision of instrumentalities for closing the slots through which coins and other moneys are introduced into receptacles provided for receiving such coins and other 15 moneys, which are usually termed "savings banks."

The special objects of my invention are the provision of such a closure which will 20 be, first, simple in construction and dependable in operation; second, which will receive different sizes of coins; third, which will receive paper money, as well as coins; and, fourth, which will prevent the unauthorized withdrawal of the money through 25 the slot.

I accomplish the aforementioned objects by means of the structure illustrated in the accompanying drawing, in which,—

30 Figure 1 is an elevation of a savings bank looking toward the portion thereof provided with the slot for introducing the money, said slot being provided with my improved closure;

35 Fig. 2 is a horizontal section on line 2—2, of Fig. 1, looking in the direction of the arrows;

40 Fig. 3 is a vertical section on line 3—3 of Fig. 2, looking in the direction of the arrows; and

Fig. 4 is a section on line 4—4 of Fig. 2, looking in the direction of the arrows.

Similar reference characters refer to similar parts throughout the several views.

45 It will be obvious that my closure may be provided with a bank of any form, which is provided with a slot for the reception of the moneys. A convenient form, however, is one of elliptical plan or horizontal section, such as is indicated in the drawing. Such a bank consists of a single shell, 5, comprising the top and sides, into which a bottom, 6, is locked. Studs or loops, 7, extend from the top of the shell, to which are 55 secured a handle or bail, 8. In order to

get a slot of sufficient length to receive coins of all dimensions, such a slot, 9, is located on one of the longer sides near the top thereof.

My improved closure is conveniently secured to the top of the shell through the instrumentality of the inner ends of the studs or loops, 7.

This closure preferably consists of a base-plate, 10, the ends of which are provided 60 with slots, 11, to receive the inner ends of the studs or loops, 7. An apron, 12, depends from one side of the plate, 10, and is provided with a slot, 13, which registers with the slot, 9, in the casing of the bank. 65 The inner face of this apron converges from above and below toward the slot, 13, at an angle of approximately 45 degrees. The ends of the apron, 12, which are as long or a trifle longer than the slots, 9, and 13, are 70 connected with the base-plate, 10, by means of webs, 14, disposed transversely to the apron. Extending between the webs, 14, are rods or pins, 15, and 16, located respectively back and just above and below the 75 upper and lower edges of the slot, 13. Mounted upon the pins, 15, and 16, are a series of cylinders, 17, the bore of which cylinders is considerably larger than the 80 diameter of the rods or pins, 15, and 16. 85

When the bank stands in normal position, these cylinders hang in front of the slot, 13, as shown in Fig. 4, and prevent any one looking into the bank. While, at the same time, they easily separate upon the introduction of any money through the slot and drop immediately back into this position upon the passage of the money. When, however, the bank is turned with the slot, 9, downward, so as to cause the money to gravitate toward 90 the slot, the cylinders, 17, will swing forward against the converged inner face of the apron, 12, which converged inner face will cause the cylinders to roll together in front of the slot, 13, and the weight of any coin 95 which might come against them from the inside, instead of separating the cylinders, tends to jam them very firmly together.

In order to prevent the coins from stacking parallel with the bottom and opposite the slot, 13, the base plate, 10, opposite the slot, is sloped downwardly, as at 18, and in order to prevent the coins from falling or being shaken transversely in front of the slot, where they might be caught in a folded piece 105 110

of paper introduced through the slot, I have provided conical projections, 19, extending downwardly from the base-plate below the lower edge of the opening, 13, which conical projections, in coöperation with the webs, 14, at the end of the apron, will prevent the lateral approach of a coin to the plane of the slot. I have shown the base-plate, 10, provided with a tail-piece, 20, which extends to and contacts with the wall of the shell opposite the slot, 13, thereby considerably strengthening the installation of my closure against displacement.

It will be observed from the foregoing description, taken in connection with the drawing, that I have provided a simple and dependable closure for the slots of banks, which will permit the insertion of coins of different dimensions and also paper money, and will effectively prevent the unauthorized withdrawal of the same.

What I claim is:—

1. A closure for coin slots and the like comprising converged longitudinal approaches for the rear of said slot, and cylinders suspended opposite said slot and in coactive relation with said approaches.
2. A closure for coin slots and the like comprising converged longitudinal approaches for the rear of said slot, pins disposed to the rear of and respectively above and below the upper and lower edges of said slot, and cylinders loosely mounted upon said pins and in coactive relation with said approaches.

Copies of this patent may be obtained for five cents each, by addressing the "Commissioner of Patents, Washington, D. C."

3. A closure for coin slots and the like comprising converged longitudinal approaches for the rear of said slot, pins disposed to the rear of and respectively above and below the upper and lower edges of said slot, and a plurality of cylinders mounted on each of said pins and in coactive relation with said approaches.

4. A closure for coin slots and the like comprising converged longitudinal approaches for the rear of said slot, cylinders suspended opposite said slot, and a projection extending into the plane of said slot and adapted to prevent the coins stacking in the plane or planes of such slot.

5. A closure for coin slots and the like comprising converged longitudinal approaches for the rear of said slot, cylinders suspended opposite said slot and in coactive relation with said approaches, and projections back of and at either side of said slot adapted to prevent the gravitation of coins laterally into the plane of said slot.

6. A closure for coin slots and the like comprising converged longitudinal approaches for the rear of said slot, and members loosely maintained opposite said slot and in coactive relation with said approaches.

Signed at Chicago, county of Cook and State of Illinois, this 28th day of August, 1917.

JOHN KORANEK
